UNITED STATES PATENT OFFICE.

JAMES A. CAMPBELL, OF CHICAGO, ILLINOIS.

DESIGN FOR AN EYEBROW-BRUSH.

• 54,815.

Specification for Design.

Patented Apr. 6, 1920.

Application filed June 12, 1919. Serial No. 303,786. Term of patent 14 years.

To all whom it may concern:

Be it known that I, JAMES A. CAMPBELL, a citizen of the United States, residing at Chicago, in the county of Cook and State of Illinois, have invented a certain new, original, and ornamental Design for Eyebrow-Brushes, of which the following is a specification, reference being had to the accompanying drawing, forming part thereof.

In said drawing, Figure 1 is a perspective view of an eyebrow brush showing my design; Fig. 2 is a side view of the same; and Fig. 3 is a view of the under side of the same.

I claim:

The ornamental design for an eyebrow brush, as shown.

JAMES A. CAMPBELL.
